Primary Examiner — T Chase Nelson*Assistant Examiner* — Sydney Margaret Parsley(74) *Attorney, Agent, or Firm* — Wood Herron & Evans LLP(57) **CLAIM**

The ornamental design for a lawn edging, as shown and described.

DESCRIPTION

FIG. 1 is an isometric view of a lawn edging showing my new design; and,

FIG. 2 is a front elevational view thereof.

Elements or portions of the design shown in broken lines show non-claimed aspects of the invention. Neither the broken lines themselves nor the portions represented by broken lines form any part of the claimed invention. The lawn edging is shown with a symbolic break in its length. The appearance of any portion of the lawn edging between the break lines forms no part of the claimed design.
